CLAIM

The ornamental design for a dental intra-oral sensor holder, as shown and described.

DESCRIPTION

FIG. 1 is a front perspective view of a dental intra-oral sensor holder showing our new design.

FIG. 2 is an exploded front perspective view thereof.

FIG. 3 is a front view thereof.

FIG. 4 is a top side view thereof.

FIG. 5 is a bottom side view thereof.

FIG. 6 is a left side view thereof.

FIG. 7 is a right side view thereof; and,

FIG. 8 is a rear side view thereof.

The broken lines showing in the drawing views are for the purpose of illustrating environmental structure and form no part of the claimed design.
